AZEOTROPIC DISTILLATION FOR RECOVERY OF AROMATIC FRACTIONS CONTAINING NAPHTHALENE

Howard V. Hess, Beacon, George B. Arnold, Glenham, and Louis Kovach, Beacon, N. Y., assignors to The Texas Company, New York, N. Y., a corporation of Delaware

Application February 10, 1951, Serial No. 210,408

1 Claim. (Cl. 202—42)

1

This invention relates to certain improvements in the azeotropic distillation of hydrocarbon oils to recover aromatic fractions rich in naphthalene.

Certain polar solvents including furfural, aniline and phenol, form minimum boiling azeotropes with paraffinic hydrocarbons boiling in the range of naphthalene and methyl naphthalenes. These solvents will also form azeotropes with other non-aromatic hydrocarbons boiling in the same temperature range as the naphthalenes.

In accordance with the invention hydrocarbon oil having a boiling range within about 300 to 500° F. is distilled with one of these azeotrope formers to distill overhead azeotropes of paraffinic hydrocarbons and azeotropes of other non-aromatic hydrocarbons. These azeotrope formers do not form azeotropes with naphthalene or methyl naphthalenes or other aromatics in this boiling range, and these materials remain in the distillation residue.

The process is applied to charging stocks, such as oils obtained from catalytic or thermal cracking or reforming processes or to virgin gas oil stocks, containing naphthalenes so as to obtain as distillation residue an aromatic fraction rich in naphthalenes.

An important feature of the invention is concerned with the recovery and re-use of the azeotrope former. This recovery is accomplished by subjecting distillate products containing the azeotrope-former to a ternary azeotropic distillation with water. By such distillation the hydrocarbon is separated from the azeotrope-former so that the hydrocarbon may be eliminated from the system and the azeotrope-former recycled.

This ternary azeotropic distillation is advantageous in preventing the build-up of low boiling hydrocarbons in a system in which the recovered azeotrope former is recycled to the distilling zone wherein the aromatics are concentrated. We find that a ternary azeotropic distillation with water in the latter zone is a disadvantage because under the temperature conditions required the presence of the water results in a steam stilling effect which impairs the desired separation of the aromatics. Thus a ternary azeotropic distillation of a cut from a catalytic cracking operation with furfural and water yielded a 75-92% sulfonatable residue product containing about 23 weight per cent naphthalene, while a binary azeotropic distillation of the same oil with furfural produced about 99% sulfonatable residue having a 41% naphthalene content. In accordance with the invention, therefore, the separation of the aromatics from the other hydrocarbons is effected with a binary azeotropic distillation with furfural, ani-

2

line, or phenol and the use of water in a ternary azeotropic distillation is restricted to the step of recovering the azeotrope former.

In an example of the invention a fraction from a catalytic cracking process having a boiling range from 360° to 450° F. and containing 10% (by wt.) naphthalene and 2% (by wt.) methyl naphthalene was subjected to azeotropic distillation with furfural with an overhead temperature of 320° F. The overhead vapors were condensed and a furfural-rich distillate was obtained containing 5.1% (by wt.) oil and 94.9% (by wt.) furfural. The oil contained 30% sulfonatable material and 0.20% naphthalenes. The aromatic concentrate withdrawn from the still as residue contained 98.9% (by wt.) oil and 1.1% (by wt.) furfural. The oil contained 90% sulfonatable material and contained 41% (by wt.) naphthalene and 5% (by wt.) methyl naphthalenes. The naphthalene recovery, based on a naphthalene balance, was 99%.

The amount of azeotrope former employed to obtain a good concentration of the aromatics by azeotropic distillation varies with the particular composition of the oil from which the aromatics are to be recovered, but in general dosages in the ratio of about 3-10:1 will be found to give satisfactory results.

The accompanying drawing is a flow diagram illustrating a preferred embodiment of the invention.

In practicing the invention a hydrocarbon oil fraction preferably having a boiling range within the range of about 300-500° F. and containing naphthalenes is subjected to azeotropic distillation with either furfural, aniline, or phenol as the azeotrope former. In describing the process by reference to the flow diagram the process will be specifically described with the use of furfural as the azeotrope former. The hydrocarbon fraction containing the aromatics and other hydrocarbons is introduced through a charging line 10 to a fractionating column 11. Furfural is admitted through a line 12. The lower section of the tower 11 is subjected to heating and the upper portion is provided with cooling or refluxing means to secure fractionation of the rising vapors. Azeotropes are formed between the paraffins and other non-aromatics and the furfural which are removed as vapor to a condenser 13, and the condensate is collected in a receiver 14. The residue which consists of the aromatic concentrate is withdrawn through a line 15.

The distillate in receiver 14 collects in two layers, a hydrocarbon rich phase and a furfural

rich phase. The furfural rich phase is withdrawn through a line 16 and recycled through line 12 to the separating tower 11.

The hydrocarbon rich phase is directed through a line 17 to a recovery still 18. Water is introduced through line 19 and a ternary azeotropic distillation is carried on in the recovery still 18. The furfural contained in the hydrocarbon rich phase which is introduced to the tower 18 forms ternary azeotropes with the water and hydrocarbons which pass overhead as vapors to a condenser 20 and the distillate is collected in the receiving drum 21. The bottoms withdrawn from tower 18 through line 22 consist of hydrocarbon oil substantially free from furfural. The distillate collecting in the receiver 21 settles in three layers, an oil rich phase, a water rich phase and a furfural rich phase. The oil and water phases are recycled through line 23 to the receiver still 18.

The furfural rich phase is withdrawn from receiver 21 and directed through a line 24 to a stripping still 25 for the removal of water. In the fractionating tower 25 a water-furfural azeotrope is distilled overhead and water-free furfural is withdrawn as a residue through a line 26 and is directed thence through line 12 to the fractionating column 11. The vapors from tower 25 pass to a condenser 27 and the distillate is collected in a receiver 28 wherein it is settled as a furfural rich phase and a water phase. The furfural rich phase is withdrawn through line 29 and recycled to the stripping still 25. The water phase is withdrawn through line 30 and is directed through line 19 to fractionator 18 or through a line 31 to a stripping tower 32. In the tower 32 the small amount of furfural contained in the water is distilled overhead, condensed in a condenser 33 and collected in receiver 34 from which it is recycled through line 35 to the settler 28. The water which is free from furfural is withdrawn through a line 36. Normally a portion of the water withdrawn through line 30 is regularly directed through line 19 to the tower 18 and the other portion is directed to the stripper 32 for the purpose of water rejection.

Make-up water may be introduced to the system as needed through line 37 and make-up furfural may be introduced as needed through a line 38.

By means of the recovery system disclosed herein, the furfural employed in effecting the separation of the aromatic constituents from the non-aromatic components of the charge oil is substantially completely recovered and is recycled in the process. The recycled furfural is moreover freed of hydrocarbons and there is no build-up of low boiling hydrocarbons in the system.

As indicative of the type of separation accomplished by the ternary azeotropic distillation in the tower 18, an example may be given in which the top temperature of the tower was held at about 210° F. with collection of three phases in receiver 21 of the following composition:

Phase	Vol. Percent	Percent Oil	Percent Water	Percent Furfural
Oil rich.....	33	94	<1	5
Water rich.....	46	Trace	94	6
Furfural rich.....	21	9	6	85

The tower 18 should ordinarily be operated at a top temperature of some 50° or more below the true initial boiling point of the feed stock to the process.

Although a preferred embodiment of the invention has been described herein, it will be understood that various changes and modifications may be made therein, while securing to a greater or less extent some or all of the benefits of the invention, without departing from the spirit and scope thereof.

We claim:

The method of concentrating aromatic hydrocarbons including naphthalene from hydrocarbon stocks boiling within a range of 300-500° F. and containing non-aromatic hydrocarbons and aromatic hydrocarbons including naphthalene that comprises subjecting such hydrocarbon stock in the absence of steam to an azeotropic distillation with furfural in a binary azeotropic distillation zone, maintaining a temperature therein to distill overhead binary azeotropes of non-aromatic hydrocarbons and furfural, withdrawing as residue the resultant aromatic concentrate containing naphthalene, collecting the overhead distillate as a furfural-rich phase and a hydrocarbon-rich phase, returning the furfural-rich phase to the binary azeotropic distillation zone, subjecting the hydrocarbon-rich phase to azeotropic distillation with water in a ternary azeotropic distillation zone, maintaining a temperature therein to distill overhead ternary azeotropes of hydrocarbons, furfural and water, withdrawing oil as residue substantially free from furfural, collecting the overhead distillate as a hydrocarbon-rich phase, a water-rich phase and a furfural-rich phase, returning the hydrocarbon-rich and water-rich phases to the ternary azeotropic distillation zone, stripping any contained water from the furfural-rich phase and recycling the stripped furfural to the binary azeotropic distillation zone.
